UNITED STATES PATENT OFFICE.

JOHN G. MACRAE, OF ASPEN, COLORADO, ASSIGNEE OF ONE-FOURTH TO GEORGE RUNTZ
AND ONE-FOURTH TO GODFREY F. ANDERSON, BOTH OF ASPEN, COLORADO.

RAIL-TIE.

1,099,305.

Specification of Letters Patent.

Patented June 9, 1914.

Application filed March 23, 1914. Serial No. 826,719.

To all whom it may concern:

Be it known that I, JOHN G. MACRAE, a citizen of the United States, residing at Aspen, in the county of Pitkin and State of Colorado, have invented certain new and useful Improvements in Rail-Ties, of which the following is a specification, reference being had to the accompanying drawings.

This invention relates to an improved rail tie and fastener and has for its primary object to provide a reinforced cement tie, and improved means for mounting the rails thereon.

The invention has for a more particular object to provide cushioning blocks arranged in recesses provided in the tie and means for retaining said blocks in place, and means carried by said blocks for securely clamping the rails thereon.

My invention has for a still further object to generally improve and simplify the construction of devices of the above character, to render the same extremely strong and durable in use and capable of manufacture at small cost.

With the above and other objects in view as will become apparent as the description proceeds, the invention consists in certain constructions, combinations and arrangements of the parts that I shall hereinafter fully describe and claim.

For a full understanding of the invention, reference is to be had to the following description and accompanying drawing, in which—

Figure 1 is a side elevation of a rail tie constructed in accordance with the present invention; Fig. 2 is a top plan view thereof; Fig. 3 is a section taken on the line 3—3 of Fig. 2; Fig. 4 is a section taken on the line 4—4 of Fig. 1; Fig. 5 is a detail perspective view of one of the parts.

Referring in detail to the drawing, 5 designates the rail tie which is formed of concrete or other plastic material in a suitable mold. This tie is provided in its upper face with the transverse recesses 6, at points adjacent each end of the tie. These recesses taper longitudinally as clearly shown 50 in Fig. 2, and the side walls thereof are oppositely beveled or inclined as indicated at 7. Metal protecting plates 8 are arranged upon these inclined side walls and are provided upon their longitudinal edges with the 55 horizontal flanges 9, the upper flanges of

said plates being countersunk in the upper face of the tie 5 while the lower flanges 9 extend into the body of the tie at the base of the recess 6. 10 designates the cushioning blocks, preferably formed of wood. These 60 blocks taper longitudinally in conformity to the tapering recesses 6 and have their longitudinal edges beveled or inclined, correspondingly to the beveled edges 7 of said recesses. These beveled side edges of the 65 cushioning blocks are adapted for frictional binding engagement against the metal protecting plates 8. These plates act as a shield or protection for the concrete tie body and prevent the edges of the recesses 6 being 70 chipped off or broken when the cushioning blocks are driven into place. In order to retain said cushioning blocks in the recesses 6 of the tie, horizontal bars 11 are disposed longitudinally upon one side of the tie across 75 the wider ends of the blocks. Bolts 12 extend through the ends of these bars and through the tie body.

Each of the cushioning blocks 10 is provided with spaced vertical openings 13 80 which are connected at their lower ends by a groove or channel 14 formed in the bottom face of the block. A U shaped bolt 15 has its end portions disposed through the openings 13, the intermediate portion of said 85 bolt seating in the groove or channel 14. The extremities of this bolt extend above the upper face of the block and clamping plates 16 are arranged thereon. The inner opposed ends of these plates are beveled for 90 engagement upon the base flange of a rail R on opposite sides of its web. Nuts 17 are threaded upon the ends of the bolt 15 to securely clamp the plates 16 in place, and hold the rail against shifting movement upon 95 the tie.

The concrete tie 5 is preferably reinforced by the upper and lower longitudinal metal rods 18 and 19 respectively. The upper rods extend only between the rail supporting blocks mounted in opposite ends of the tie while the lower bars 19 extend substantially the entire length of the tie body. The extremities of these reinforcing rods or bars are angularly bent and extended downwardly as shown at 20. By means of these rods, it will be appreciated that the tie structure is greatly strengthened.

From the foregoing description, taken in connection with the accompanying drawing,

it is believed that the construction, manner of operation and several advantages of my invention will be clearly and fully understood.

5 The rail supporting blocks may be very easily and quickly inserted in the recesses of the tie and secured in position. These blocks which as above stated, are constructed of wood, serve as cushions for the rails and 10 permit of a vertical movement of the rail in the passage of the train over the tie.

The device as a whole is extremely simple in its construction, strong and durable in practical use and may be manufactured at 15 small cost.

While I have shown and described the preferred construction and arrangement of the several elements, employed, it will be understood that the invention is susceptible of 20 considerable modification therein and I therefore reserve the privilege of resorting to all such legitimate changes as may be fairly embodied within the spirit and scope of the invention, as claimed.

25 Having thus described the invention, what is claimed is:

1. The combination with a tie provided in its upper face and adjacent its ends with transversely disposed longitudinally tapering recesses, of metal plates arranged upon the opposite side walls of said recesses and having parallel horizontal flanges formed on their longitudinal edges, the lower flanges of said plates extending into the body of the 30 tie at the base of the recess, and the upper flanges being counter-sunk in the upper surface of the tie, tapering cushioning blocks adapted for insertion into said recesses and 35 frictionally engaging said reinforcing plates, means for retaining said blocks in the recesses of the tie, and means carried by the respective blocks for securing a rail thereon.

2. The combination with a concrete tie 40 provided in its upper surface adjacent each

end with a transversely disposed tapering recess, the side walls of which are oppositely inclined, of metal reinforcing plates arranged upon the side walls of each recess, each of said plates being provided with parallel horizontal flanges on its longitudinal edges, the lower flange extending into the body of the tie and the upper flange being counter-sunk in the upper face of said tie, tapering cushioning blocks adapted for insertion into said recesses and frictionally engaging said plates, longitudinally disposed bars secured upon one side of the tie across the wider ends of said blocks to retain the same in place and means carried by the respective blocks for securing the rail thereon.

3. The combination with a concrete tie provided in its upper face and adjacent each end with a transversely disposed tapering recess having oppositely inclined side walls, of reinforcing plates arranged upon said inclined side walls and embedded in the tie body, tapering cushioning blocks adapted for insertion into said recesses and frictionally engaging said plates, longitudinally disposed bars arranged upon one side of the tie across the wider ends of said blocks, bolts extending transversely through the tie and through the ends of said bars, each of said blocks being provided with spaced vertical openings and having a groove in its bottom face connecting said openings, a U shaped bolt extending through said openings and seated in said groove, the ends of said bolt extending above the upper surface of the 75 block, and rail clamping plates on the ends of said bolt to secure a rail in position upon the block.

In testimony whereof I hereunto affix my signature in the presence of two witnesses.

JOHN G. MACRAE.
